UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAW-BAR AND YOKE CONNECTION FOR RAILWAY-CARS.

1,099,197.

Specification of Letters-Patent.

Patented June 9, 1914.

Application filed December 30, 1910. Serial No. 600,066.

To all whom it may concern:

Be it known that I, JOHN F. O'CONNOR, a citizen of the United States, residing at Chicago, in the county of Cook and State of Illinois, have invented a new and useful Improvement in Draw-Bar and Yoke Connections for Railway-Cars, of which the following is a specification.

My invention relates to improvements in draw-bar and draft yoke connections for railway cars.

The object of my invention is to provide an improved construction of draw-bar and yoke connection which will obviate or overcome the tendency of the pair of rivets to shear which connect the draft yoke with the draw-bar under heavy strains or blows. To practically accomplish this object or result, and herein my invention consists, I provide the upper and lower limbs of the draft yoke on their inner faces with integral projections through which the rear portion of the front rivet hole is bored, and through which the front portion of the rear rivet hole is bored, and the draw-bar with slots on its upper and lower faces preferably of dovetail shape to receive said projections or enlargements, thus materially increasing the bearing face of the draft yoke against the adjacent peripheral faces of the rivets, and making it necessary for a portion of the draw-bar itself to be sheared off before the rivets can shear. To adapt the draw-bar to receive a draft yoke of the ordinary construction, filler plates are provided which may be inserted in the transverse slots in the upper and lower faces of the draw-bar.

In the accompanying drawing forming a part of this specification, Figure 1 is a plan view of a draw-bar and draft yoke connection embodying my invention. Fig. 2 is a side elevation, partly in cross section, on line 2—2 of Fig. 1. Fig. 3 is a detail plan view of the draw-bar with the draft yoke removed. Fig. 4 is a side elevation of the draw-bar with the draft yoke removed. Fig. 5 is a detail inner face view of one of the limbs of the draft yoke. Fig. 6 is a detail side view of one limb of the draft yoke. Fig. 7 is a detail side view of the other limb of the draft yoke. Fig. 8 is a detail plan view of one limb of the draft yoke showing the same before the rivet holes are bored.

Fig. 9 is a detail section on line 9—9 of Fig. 8. Fig. 10 is a detail plan view of one of the filler plates and Fig. 11 is a detail section on line 11—11 of Fig. 10.

In the drawing, 1 represents a draw-bar and 2 the draft yoke. The draw-bar preferably has the customary transverse grooves 3, 4 in its upper and lower faces to receive the bent ends or gibbs 5 on the front ends of the draft yoke. The draw-bar is also provided on its upper and lower faces with transverse slots 6, 7, preferably of dovetail shape and of a width corresponding to the distance between the centers of the rivet holes 8, 9 in the draw-bar.

The transverse slots 6, 7 are adapted to receive the integral lugs or projections 10, 11 on the inner faces of the draft yoke limbs 13, 14, the length of these lugs corresponding approximately to the distance between the centers of the rivet holes 15, 16 in the draft yoke which correspond and register with the rivet holes in the draw-bar. The front rivet hole 16 thus extends through the front end of the lugs or projections 10 and 11 and the rear rivet hole 15 extends through the rear end portion of the lugs or projections 10 and 11, thus giving each limb of the draft yoke a more extended bearing or engagement with the adjacent peripheral faces of the connecting rivets and very greatly adding to the strength of the connection and practically preventing all possibility of the connecting rivets shearing as the rivet reinforcing lugs on the draft yoke have to shear off or else the portions of the draw-bar directly in front or rear of the transverse slots 6, 7 in which the rivet reinforcing lugs or projections 10 and 11 of the draft yoke fit.

To adapt the draw-bar for use in connection with an ordinary standard or Master Car Builders' draft yoke which does not have my rivet reinforcing lugs or projections, I provide dovetail filler plates 17 which may be driven into the dovetail slots 6, 7 on the upper and lower faces of the draw-bar to fill up the slots or grooves 6, 7. Each of the filler plates 17 is provided with front and rear semi-circular recesses 18, 19 to receive the rivets 26.

In my invention, the rivet reinforcing lugs or projections on the inner faces of the draft yoke limbs do not require to be accurately

shaped or located, as the rivet holes are bored through these lugs or projections in drilling the yoke in the regular way from the outside to a templet or jig, the drill will 5 cut the rivet engaging ends of the lug and make it accurately fit the adjacent walls of the rivets.

With my invention, the faces or shoulders 10 on the member 1, and the corresponding faces or shoulders 21 on the lug 10, fit the 15 sides of the rivets and are disposed on opposite sides thereof. Since these faces or shoulders are formed by drilling, as previously described, they must accurately fit 20 the rivets, and it is apparent that it is unnecessary to have a correct fit between the walls or shoulders 23 of the members 10, with the walls or shoulders 22 of the member 1. This construction results in a great practical saving of labor and time and expense 25 when the parts are being assembled, and at

the same time produces a strong and accurate connection between the parts.

I claim:

In a draw-bar and draft yoke connection, the combination with a draw-bar having a pair of rivet holes and transverse slots in its opposite faces corresponding in width to the space between the centers of the rivet holes of a draft yoke having a pair of rivet holes through its limbs and rivet reinforcing lugs on its inner faces through the extremities of which the inner or adjacent portions of the rivet holes extend, said rivet reinforcing lugs on the draft yoke limbs fitting in said transverse slots of the draw-bar, substantially as specified.

JOHN F. O'CONNOR.
